UNITED STATES PATENT OFFICE.

WILFRED CADORETTE, OF HOLYOKE, MASSACHUSETTS.

ATTACHMENT TO MOVING-PICTURE MACHINES.

Application filed August 2, 1924. Serial No. 729,809.

This invention relates to improvements in
mechanisms on picture machines.

The particular object of my invention is to
materially reduce the fire hazard which is in-
5 cident to the use of these machines. At the
present time fire often occurs when the ma-
chine, for any reason fails to operate prop-
erly, as for instance, when the mechanism
which feeds the film fails to operate prop-
10 erly, causing the film to come to a standstill.
If this occurs the film often takes fire due
to the intense heat from the arc lamp which
is employed to supply the necessary illumina-
tion for projecting the film onto the screen.
15 My invention is therefore directed to remove
and effectively overcome this fire risk by pro-
viding automatic means for closing the shut-
ter, or door which is located between the film
and the source of illumination.

20 This shutter is designed to automatically
operate when any one of the following con-
ditions of operation of the machine should
arise, namely, should the upper supply reel
not be properly wound, or, the holes in the
25 film which receive the teeth of the sprocket
wheel which feeds the film become stripped
or torn, or, should the upper sprocket wheel
become loosened for any reason, or, should
the film slip off from the upper sprocket
30 wheel, or, should the film become disengaged
from the intermittent feed wheel, or should
the plate which is provided with an aperture
stick or become inoperative due to too
much tension on the tension shoe, or, should
35 the speed of operation of the machine be too
slow, or, should the film slip, or, should the
driving belt break, or, should the friction
drive slip, or should the current to the motor
be cut off.

40 Other objects and nature of the invention
will appear in the body of the specification
and will be particularly pointed out in the
claims.

45 Referring to drawings which form a part
of the specification:—

Fig. 1 is a diagrammatic view of the gen-
eral arrangement of the essential parts of a
moving picture machine, showing the supply
and take up reel, the shutter, and the means
50 for operating the film.

Fig. 2 is a detail side view of a portion of
the movable guard plate of the film.

Fig. 2^a is a detail view of a portion of the
guard plate.

55 Fig. 3 is a side view of the movable shut-
ter.

Fig. 4 is an enlarged edge view of the
guard plate, the solenoid for automatically
operating the shutter, and the mechanism
for opening or closing the electric circuit. 60

Fig. 5 is a detail sectional view of the
solenoid and its movable core.

Fig. 6 is an enlarged detail view of the
film guard plate and parts operated thereby
for opening or closing the electric circuit 65
switch.

Fig. 7 is a sectional view of the centrifugal
switch for opening or closing the electric
circuit of the solenoid.

Fig. 8 is a detail sectional view on the line 70
8—8 of Fig. 7.

Fig. 9 is a detail view of the connection
between the centrifugal switch and link for
operating the film guard plate.

Fig. 10 is a view of the switch frame 75
which contains the motor starting and stop-
ping buttons.

Fig. 11 is a diagrammatic view of the elec-
tric connections, and

Fig. 12 is a detail view of the starting 80
switch.

Referring to the drawings in detail:

1 designates the reel on which the film to
be exhibited on the screen is wound. 2 the
screen. 3 the take up reel for the film, 4 85
the film which is formed near its side edges
with the perforations 5 and 6 to receive the
spurs or projections 7 on the wheels 9 and 10,
and 11. The usual guide rolls are indicated
at 12, 13, 14, 15, and 16. 17 and 18 are the 90
usual tension rolls for maintaining the film
tight and in close contact with the toothed
wheel 9. It is to be understood that the film
has imparted thereto the usual intermittent
or step-by-step motion by means of the 95
toothed wheel 10. 19 designates the usual
spaced tension plates having the aligned
openings 20 and 21 between which the
film 4 passes. 22 designates the electric
arc lamp for supplying the illumination 100

for the film, the condensed rays being
indicated at 23. 24 is the usual shutter
for cutting off the rays of light and heat
when the film is not to be exhibited or for
other reasons. This shutter is securely con-
nected to the rod 25, by means of the set
screw 26. Attached to the shaft 25 is a de-
pending curved arm 27 which operates as a
weight. 105

Referring now to the specific features of
my improvements for protecting the film 4
from being ignited from the arc lamp 22

should the machine fail to operate for any of the reasons stated above, 28 designates what I term a film guard plate which is curved, as shown. This plate is formed with the track-ways or elevated ridges 29 along and against which film 4 travels, in order to prevent the surface of the film from being scratched or injured. This plate is secured to the shaft or rod 30 by means of the set screw 31. The rod is formed with a depending curved part 32 which cooperates with the electric circuit switch controlling member 33 (see Fig. 6) that includes the arm 34. It is formed with the curved end 35 that cooperates with the switch member 35'. This arm is pivotally mounted on the shaft 36. Integrally connected to the arm 34 is a depending member 37 to the lower end of which is pivotally connected the link 38 that is attached at its other end to the centrifugal clutch 76, and, integral with the member 37 is the upwardly curved arm 39 which lies in the path of the depending curved part 32 of the guard plate 29.

For the purpose of electrically and automatically operating the shutter 24 a solenoid 40 is provided in the bore of which is placed the plunger 41 that is composed of a bundle of soft iron plates in order to permit the plunger to be drawn into the bore 42, since an alternating electric current is employed for energizing the solenoid. 43 is a part which is attached to the plunger 41. It is composed of some suitable nonmagnetic material as fibre or brass. The inner end of the part 43 will engage the curved arm 27 of the shutter 24, when the solenoid is energized, and retain the shutter in its elevated or horizontal position, as long as the solenoid is energized, as shown. Should the solenoid become deenergized for any reason the shutter will drop into its closed or vertical position, due to the force of gravity. Normally, therefore, the solenoid is electrically energized when the machine is in operation.

The electrical connections for the solenoid are as follows: The source of alternating current is indicated at 44, see Fig. 11. 45 is a step down transformer having the primary winding 46 and the two sections of the secondary windings, 47 and 48, for taking off current of 6 and 9 volts respectively, if desired. 49 is a wire connected to one terminal of the secondary coil 48 at 50. This wire leads to the starting switch terminal 51 which is connected to the contact bar 52. 53 is a push button rod that is normally retained in an elevated position by the spring 54 which is normally under compression. It rests on the plate 55 at one end and the shoulder 56 at its opposite end. 57 is a conducting plate which is attached to the rod 53. 58 is a second contact bar with which the plate 57 engages when the rod 53 is depressed. This bar is connected to the wire 59 at 60 which extends to the electromagnet winding 61 and back to the other terminal of the secondary coil 48 of the transformer 45. 61 is an armature 70 pivotally connected at 62 to a fixed support. This armature is normally elevated by the spring 63 and is formed with the two contact terminals 64 and 65 which engage the terminals 66 and 67 of the operating motor 68. When these terminals are closed the motor then receives current direct from the main source of alternating current 44 at a voltage of 110. The wires which connect the motor 68 to the source are indicated at 69 and 70. When the main switch is closed at 44 to start the motor 68 the circuit to the solenoid 40 is completed as follows: 71 is a wire which is connected to the terminal 72 of the secondary winding, this wire is connected to one of the terminals of the solenoid at 73. The other terminal 74 of the solenoid winding is connected to a wire 75 which leads to the centrifugal clutch 76 shown in detail in the enlarged sectional view of Fig. 7, which clutch is secured to the shaft 77 that serves as the ground side of the circuit through the solenoid. This ground connection being indicated in Fig. 11 by the dotted line 78 and by the full line 79 in Fig. 7 which is electrically connected to the frame 79 of the machine.

The construction of the centrifugal clutch comprises a plate 80 which is secured to the shaft 77 with the set screw 81. It is formed with the annular flange 82 and hub part 83 in each of which is an opening 84 and 85 to receive the rods 86. Loosely mounted on these rods are the weights 87 which are normally retained against hub 83 by the reaction of the expansion springs 88 on the rods 86 and between the flange 84 and a recess, as shown, in the weights. Attached to the outer ends of the rods 87 are the metal electric contact shoes or plates 89, which, when the speed of the clutch is sufficient, will be thrown outward by the weights into contact with the inner surface of the annular flange 90 thus closing the electric circuit from wire 75 to the metallic plate 91, the hub part 92 of the disk 93 which is insulated from the shaft 77 by means of the pieces 94 and 95. 96 is an oil hole for the bearing. The plate 91 is formed with the opening as shown to permit the shaft to pass through without contacting. The circuit from the wire 75 is therefore completed to the shaft 77 and ground when the speed is sufficient. It is to be understood that the motor 68 is directly connected to the shaft 77 through suitable gearing, not shown. This connection is conventionally indicated by the dotted lines 97 in Fig. 11 and gear 98 in Fig. 7. It will therefore be seen that the centrifugal clutch 76 will not become operative until the mo-

tor 68 reaches a predetermined speed, therefore, there will not be any current flowing through the solenoid 40 until the correct speed of the motor is attained and the machine is in full operation. When this condition is reached then the shutter 24 is automatically moved into its open horizontal position shown in full lines in Fig. 1 to permit the light rays from the arc lamp 22 to pass through the film 4 and project the pictures onto the screen 2. The shutter 24 is operated by the plunger 43 when the solenoid is electrically energized.

99 designates a metallic plate that is secured to the frame piece 100 with the screws 101 which pass through the blocks of insulation 102. This plate is for the purpose of forming a good contact with frame 100 and wire 78. Connected to the disk 93 is the link 38 with the pin 103.

In order to render the pictures on the screen continuous it is often times necessary to employ a second machine and to "cut in" or automatically put the second machine in operation, means is provided for this purpose which comprises an arm 104 that is pivotally attached at 105 to a fixed support. This arm carries a roller 106 which normally rests upon the film 4 as it is unwound from the supply reel 1, and therefore moves inward towards the shaft of the reel. For the purpose of electrically closing the circuit to the motor 68 a plate 107 is operated by the end of the arm 104. This arm operates the contact brush 108 which momentarily closes the motor circuit through its contact with the rods 109 (see Fig. 1), which are connected to the wires 110 and 111. This circuit is closed about two seconds of time. The wire 110 is connected to the wire 59, and the wire 111 is connected to the wire 49. 112 is a metal contact plate of the stop switch 113 which is normally in contact with the contact strips 114 and 115.

The strip 114 is connected to the wire 116 which extends to the terminals 117 and 118 of the make and break switch which automatically controls the opening or closing of the shutter 24. The circuit through the electromagnet 61 which maintains the contacts 64, 65, 66, and 67 closed is as follows: from one terminal of the secondary winding 48, windings of the electromagnet 61, wire 59, wire 110, contact brush 108, rods 109, wire 111, wire 49 to the other terminal of the winding 48. Current also flows from wire 59, strip 115, plate 112, strip 114, wire 116 to contacts 117, 118 to ground. It will be seen that in order to stop the operation of the motor 68 it is only necessary to push downward on the "stop" switch 113 which moves the plate 112 away from the contact strips 114 and 115. In order to again start the motor 68 it is only necessary to press downward the "start" switch 53. It will

also be seen that when the contacts 117 and 118 are opened the solenoid 40 is deenergized.

Referring now to the operation of the machine and considering the parts in their normal position shown with the shutter 24 open and the guard plate 28 in its normal or full line position. Assume that the film 4 from the reel 1 for some reason is not fed forward its correct speed, the pressure of the film against the inside of the plate 28 is then reduced. The plate 28 will now occupy the position shown in dotted lines 28' (see Fig. 1) with the result that the arm 34 will fall away from its central or horizontal position. The depending arm 32 will assume the dotted position 32' which position removes the support for the arm 34. This operation permits the electric contacts 117 and 118 to open and consequently deenergizes the solenoid 40 and electromagnet 61. The plunger 41 is now moved outward by the weighted arm 27 which is attached to the shutter 24 as it falls into its closed position shown in dotted lines in Fig. 4. The elevations 119 and 120 on the contact strip 118 are arranged to form a curved surface with the pivot of the arm 34 as a center, and of such a size that if the arm 34 assumes any position either above or below these elevations the contact strip 118 will open the circuit. As soon as the shutter closes the heat from the electric arc is instantly shut off. In order to resume operations again the button 53 is pushed downward as before. Should the film 4 for any reason be fed too fast the guard plate 28 will be forced outward by the pressure of the film into the dotted position 28'' (see Fig. 4) the normal position of the arm 32 is now moved towards the right into the dotted position 32''. This operation lifts the arm 34 and again the contacts 117 and 118 will open the circuit causing the solenoid to become deenergized and the shutter 24 to close.

The centrifugal clutch normally operates to move the disk 93 about the shaft by reason of the shoes 89 engaging the rim 90. This will cause the disk 93 to turn, and, through the link 38 will maintain the plate 28 in a balanced position, and part 37 will be engaged by 34. There are therefore two ways of opening the circuit through the solenoid, one, by the action of the motor if the speed is too high and the other by the operation of the film.

The construction and mounting of the plate 28 is such that it is nicely balanced about its pivot 30.

It will be observed therefore that the travel of the film against the guard plate 28 exerts a definite normal pressure at its correct speed and should this pressure be slightly increased or diminished the plate

28 will cause the switch members 117 and 118 to open thus deenergizing the solenoid.

It should be observed that the end 104 of the arm 104 in passing from the beginning of the unwinding of the reel to near its end momentarily engages the button 107 in order to start the second machine. After the end leaves the button the circuit is again opened.

10. What I claim is:—

1. In a machine for the purpose described, the combination with let off and take up reels for the film, spaced tension plates having openings and between which the film travels, a pivotally mounted shutter for cutting off the heat rays from the source of light which illuminates the film that passes through openings in the plates, means comprising electro-mechanical devices for maintaining the shutter in its open position, and means comprising a film engaging plate to permit the shutter to close should the rate of travel of the film be either increased or decreased, said film being normally in engagement with the plate.

2. In a machine for the purpose described, the combination with let off and take up reels for the film, spaced tension plates having openings and between which the film travels, a pivotally mounted shutter for cutting off the heat rays from the source of light which illuminates the film that passes through openings in the plates, electrical means for maintaining the shutter in its open position, and a pivotally mounted plate along which the film normally travels to permit the shutter to close should the rate of travel of the film be either increased or decreased.

3. The combination with a shutter device to prevent the heat rays from reaching the film in a motion picture machine, of a pivotally mounted plate which is engaged by the traveling film when in motion, means for maintaining the shutter open when the film is moving at its normal speed, and in contact with the plate but operative to close the shutter should the normal speed be either increased or diminished.

4. The combination with the shutter of a moving picture machine, a member which is engaged by the film to exert a definite pressure when moving at its normal rate of travel, means cooperating with the member for engaging the shutter to retain it in an open position at such speed but operating to close the shutter should the rate of travel be either increased or diminished, said means comprising an electromechanical device which engages the shutter, an electric circuit including the said device, a make and break device which is operated by the member.

5. In a motion picture machine, the combination with a let off and take up reel for

the film, a pivoted plate member along which the film travels, a shutter, an electromagnetic device for operating the shutter, for moving it into its open position, an electric circuit which includes the said device, a switch in the circuit, and cooperating means between the plate and switch for opening the circuit when the plate member is moved by the film out of its normal position.

6. In a motion picture machine, the combination with a let off and take up reel for the film, a pivoted plate member along which the film travels, a shutter, an electromagnetic device for operating the shutter, for moving it into its open position, an electric circuit which includes the said device, a switch in the circuit, and cooperating means between the plate and switch for opening the circuit when the plate member is moved by the film out of its normal position, said means comprising a part on the member, an arm engaged by the part that engages the switch device, the switch being so constructed that when the arm assumes any position but its normal one the switch will open the circuit and deenergize the electromagnetic device permitting the shutter to automatically close.

7. The combination with the moving film of a motion picture machine, a pivotally mounted shutter which closes by the operation of gravity, an arm on the shutter, a solenoid, a plunger operated by the solenoid for engaging the arm of the shutter for moving it into its open position when the solenoid is energized, an electric circuit including the windings of the solenoid, an electric motor for operating the film, a centrifugally operated switch and clutch member driven by the motor and included in the circuit whereby the solenoid is deenergized when the speed of the clutch member is below normal and whereby the shutter will automatically close.

8. The combination with the pivotally mounted shutter of a moving picture machine, an electromechanical device for maintaining the shutter in its open position when energized, an electric circuit including said device, a source of electromotive power, an electric motor operated therefrom for operating the machine, a starting switch in the circuit for the motor, an electromagnet for closing the circuit to the motor, the electromechanical device being included in the same circuit as the electromagnet, a switch in this circuit, a movable plate against which the film of the machine exerts a pressure, and cooperating means between the plate and switch.

9. The combination with a moving film, of a shutter, a solenoid, a plunger therein for engaging the shutter to retain it in an open position when energized, a movable plate against and along which the film trav-

els to maintain it in a definite position by exerting pressure thereon, an electric circuit which includes the solenoid windings, a switch in the circuit, and cooperating devices between plate and the switch whereby when the pressure of the film on the plate is either increased or decreased the circuit is opened and the shutter closes.

10. A shutter closing device for moving picture machines having, in combination, a movable member against which the travel-

ling film presses, means for operating the shutter from the movable member, means for maintaining the member in a balanced vertical position against the pressure of the moving film but permitting the member to operate to close the shutter when the balance is disturbed by reason of an increase or decrease of pressure by the moving film on the member. 15

WILFRED CADORETTE. [L. S.]
